UNITED STATES PATENT OFFICE.

STANLEY E. MAVES, OF FREEPORT, ILLINOIS, ASSIGNOR TO WESTERN NEWELL MANUFACTURING COMPANY, OF FREEPORT, ILLINOIS, A CORPORATION OF ILLINOIS.

DESIGN FOR A CURTAIN ROD.

Application filed December 29, 1928. Serial No. 29,440. Term of patent 14 years.

To all whom it may concern:

Be it known that I, STANLEY E. MAVES, a citizen of the United States, residing at Freeport, in the county of Stephenson and State of Illinois, have invented a new, original, and ornamental Design for Curtain Rod, of which the following is a specification, reference being had to the accompanying drawing, forming a part thereof.

Figure 1 is a perspective view of the curtain rod, showing my new design, and

Figure 2 is an enlarged detailed view of the design feature contained between the area designated by the arrows in Figure 1.

I claim:

The ornamental design for a curtain rod, substantially as shown.

STANLEY E. MAVES.
